UNITED STATES PATENT OFFICE.

HENRY NOEL POTTER, OF PITTSBURG, PENNSYLVANIA, ASSIGNOR TO
GEORGE WESTINGHOUSE, OF SAME PLACE.

MAGAZINE BALLAST FOR ELECTRIC LAMPS.

SPECIFICATION forming part of Letters Patent No. 669,594, dated March 12, 1901.

Application filed June 4, 1900. Serial No. 18,956. (No model.)

To all whom it may concern:

Be it known that I, HENRY NOEL POTTER, a citizen of the United States, residing at Pittsburg, in the county of Allegheny and State of Pennsylvania, have invented a new and useful Improvement in Magazine Ballast for Electric Lamps, of which the following is a specification.

My invention relates to electric lamps the light-emitting bodies of which are conductive only when hot and decrease in resistance with increments of temperature, and particularly to ballast devices employed in connection with such light-emitting bodies.

The object of my invention is to provide a ballast device that shall have greater possibilities of long-continued service without destruction than those heretofore employed.

In the accompanying drawings, Figure 1 is a perspective view of a ballast device constructed in accordance with my invention, and Fig. 2 is a diagrammatic view showing the electrical arrangement of the resistance-wires.

Where iron wire is employed as steadyng or ballast resistance, it has been my practice to locate such resistance-wire in an air-tight chamber filled with hydrogen, and if the resistance-wires are carefully prepared and surrounded by pure dry hydrogen there is ordinarily no reason why they should not be used indefinitely without injury unless subjected to a sufficiently high voltage to actually melt the iron wire. There is, however, always a possibility that some of the conditions incident to perfect construction may be absent, and I have therefore devised the means shown in the drawings, to which reference will now be had.

The chamber 1 is preferably a glass tube filled with hydrogen and has an inwardly-projecting portion 2, through which the terminal-wires 3, 4, 5, and 6 project and in which they are sealed. The part 2 also supports a rod 7, the one end of which is bent into approximately a flat spiral form having two approximately straight sides 8 and 9, though this part of the device may be given many forms that differ from that shown without in any way affecting the character or scope of the invention.

The ballast-wires are disposed as follows: The length 10 is joined to the inner end of terminal-wire 3, is wound about the portion 8 of the support, and then returned to form 55 the length 11, the outer end of which is joined to the terminal-wire 6. In the same manner the length 12 is joined at one end to the terminal-wire 4, is wound about the portion 9 of the support, and returned as length 13, to be 60 joined at its outer end to the terminal-wire 5. Each of the terminal-wires 3, 4, 5, and 6 is provided with a terminal-plug 14, preferably of soft substantially non-oxidizable metal, such as aluminium, for the purpose 65 of engagement with terminal-sockets in order to connect any two of the ballast-resistance lengths in series with each other and with the glower.

It will be observed that any one of the four 70 ballast-wire lengths 10, 11, 12, and 13 may be substituted for any other one by removing the plug 14 corresponding to the first length and inserting in its place one corresponding to the substitute length. For example, as 75 assuming that lengths 10 and 11 constitute the active ballast and the length 10 becomes destroyed, the plug 14 corresponding to either the length 12 or the length 13 may be inserted in the socket from which the plug correspond- 80 ing to the length 10 has been removed, and the ballast will then be in operative condition and substantially the same as it was originally so far as the operative parts are concerned. In the same manner if another of 85 the lengths becomes broken or otherwise destroyed it may be replaced in the circuit by merely removing its plug from the socket and substituting therefor the plug corresponding to another length. 90

In case the gas in the chamber contains traces of oxygen or other gas injurious to the iron ballast-wire the chemical reactions which result in the gradual destruction of one of the ballast-wire lengths will remove from the atmosphere within the chamber all or a portion of the injurious gases by the formation of inert iron compounds. The tendency to disintegration in the lengths subsequently employed as ballast will therefore be less. It 100 will therefore be seen that by slightly increasing the original cost of the ballast device by

doubling up an inexpensive element the life of the ballast as a whole may be greatly increased.

I claim as my invention—

- 5 1. A magazine ballast device for electric lamps of the type described comprising three or more ballast-conductors electrically connected together at one end and severally provided at their other ends with terminal plugs 10 for making removable connection with the glower-circuit.
- 15 2. A magazine ballast device for electric lamps of the type described comprising a chamber, three or more ballast-conductors located therein, means for electrically and mechanically connecting the inner ends of said conductors and means outside said chamber for connecting any two of said conductors in the glower-circuit.
- 20 3. A magazine ballast device for electric lamps of the type described, comprising three or more conductors a supporting-rod to which said conductors are joined in "star" connec-

tion, an inclosing chamber for said conductors containing hydrogen and circuit-connecting 25 plugs on the outer ends of said conductors.

4. A magazine ballast for electric lamps of the type described comprising a chamber filled with hydrogen, three or more strands of iron wire supported in said chamber and electrically connected at their inner ends and terminal leads for said iron-wire strands that are severally provided with contact-plugs. 30

5. A magazine ballast device for electric lamps of the type described, consisting of 35 three or more half-ballasts connected together at their inner ends and at their outer ends provided with terminals whereby any two of the said half-ballasts may be connected in series with each other and with the glower. 40

In testimony whereof I have hereunto subscribed my name this 1st day of June, 1900.

HENRY NOËL POTTER.
